UNITED STATES PATENT OFFICE.

TAYLOR CALHOUN RHODES, OF ST. PAUL, MINNESOTA.

REFLECTING MEANS.

Application filed July 26, 1922. Serial No. 577,659.

To all whom it may concern:

Be it known that I, TAYLOR CALHOUN RHODES, a citizen of the United States, and a resident of St. Paul, in the county of Ramsey and State of Minnesota, have invented certain new and useful Improvements in Reflecting Means, of which the following is a specification.

One object of my invention is to provide a reflector of such construction that substantially all of the light from a source of light, hereinafter referred to as bulb, used therewith will be projected forwardly and so directed as to fall where needed for giving the best illumination.

Another object is to provide a reflector so adapted as to have a bulb positioned within the reflector at the focal point of the reflector, the characteristics of the inner curved surface of the reflector being such that all light, except that thrown directly forward from the bulb to the desired field of light, will itself be reflected from one curved surface of the reflector to another and thence to the focal point of the reflector, and will either pass through a second similar series of reflections so as to be, or will then be forwardly thrown from the focal point co-incident with those rays which are not reflected, 30 but which pass through an opening to this field of light.

Another object is to provide a bulb having a filament therein substantially at the focal point of the bulb, the shape of the bulb being such that when it is surrounded by a reflector having a similar contour or is coated either inside or outside by a reflecting substance over such portion of its surface as corresponds to the above described reflector, 40 said reflector will reflect all light fallen thereon through the focal point of the bulb in the same manner as above described.

In general the objects of my invention are to provide a combination of reflectors that will as nearly as possible gather all the rays of light from the source of light except those that fall in a given field of light and reflect the rays so gathered through the source of light and co-incident with the rays that fall 50 into the desired field of light.

With these and incidental objects in view, the invention consists of certain novel features of construction and combination of parts, the essential elements of which are hereinafter described with reference to the

drawings which accompany and form a part of this specification.

In the drawings:

Figure 1 is a vertical section taken through the axis of a semaphore lamp embodying this invention; 60

Figure 2 is a section taken on the line 2-2, Figure 1;

Figure 3 is an enlarged detail of the adjustment nuts for the bulb socket; 65

Figure 4 is a section taken on the line 4-4 of Figure 3 looking downwardly;

Figure 5 is a sectional view taken on the line 5-5 of Figure 3 looking in the direction of the arrow, the socket being omitted; 70

Figure 6 is a schematic view of a reflector showing the manner in which rays are directed through the focal point of the reflector;

Figure 7 is a schematic diagram illustrating the position of a plurality of suppositional flat mirrors as described in reference to the development of the contour of my reflector; 75

Figure 8 is a schematic view of a special construction of the reflector designed to throw all of the light upon the road ahead and below a predetermined height and also in equal volumes upon equal road distances; 80

Figure 9 is a schematic view of the reflector of the style shown in Figure 8 and illustrating the manner in which the light rays may pass through the focal point of the reflector to cast equal volumes upon equal road distances; 85

Figure 10 is a composite view partially in rear elevation of the reflector shown in Figure 9 and partially in vertical section on the line 10-10 of Figure 9;

Figure 11 is a vertical section taken through the longitudinal axis of a modified construction of my invention in which the lamp bulb itself is made in the shape desired for the reflector and is tightly enclosed in a reflector shell, or may be coated by reflecting material on inner or outer surfaces, except that portion thereof which corresponds to the opening of the reflector. 95

Figure 12 is a diagram used in describing the theory of equal areas of light; 105

Figure 13 is a diagram showing the development of the tangents to which the irregular curve of my reflector may be drawn.

In the selected embodiment of the invention shown in Figure 1, the lamp body 15 110

contains a substantially egg-shaped reflector 16 having a circular opening 34 at its axially central forward end. The reflector is adjustably mounted therein by a screw and nut connection 17. A light bulb is positioned within the reflector 16 at its focal point 27. The bulb preferably employed is one which provides a concentrated light source with a minimum of obstruction to reflected rays.

10 This bulb has a slender stem 19 extending downwardly through an aperture 70, provided in the lower forward portion of the reflector, and terminating in a small base received within the bayonet socket 21. The 15 socket is carried by a hollow threaded stem 22 adjustably supported by the body 15. The stem 22 is received in threaded engagement with the nut 23, the annularly flaring head of which is supported by the lower 20 wall of the lamp body 15. The exterior of the shank of the nut 23 is square and extends through the circular aperture in the lower wall. The nut 23 may be adjustably rotated by means of a driving ring 24 which 25 is exteriorly hexagonal and interiorly square to receive the shank of the nut 23 therethrough. This ring 24 is also of a diameter greater than the aperture. The aperture in the lamp wall is large enough to permit 30 horizontal displacement of the nut 23 for the desired adjustment of the bulb. The head of the nut 23 and ring 24 are sufficiently large to close entirely the wall aperture in any of their adjusted positions. A lock 35 nut 25 is received in threaded engagement on the stem 22 and holds all parts in adjusted position. Obviously, the length of the stem of the nut 23 must be less than the sum of the thickness of ring 24 and wall 15.

40 The screw and nut adjustment 17 is adapted to hold the reflector 16 in a plurality of adjusted positions and is substantially similar in construction and operation to the adjustment of the stem 22.

45 On a plane perpendicular to the horizontal axis of the reflector at its focal point 27, two pairs of minute holes 40-40 are drilled diametrically opposite each other; one pair being in upper right and lower left quadrants and the other at right angles thereto. By sighting through these holes the filament of the bulb may be properly adjusted within the focal point of the reflector. Holes 50 are drilled in lamp body 15 in like relation to the focal point of the lens 20 to be used therewith. They may be threaded and closed by screws. By lining up holes 40 and 50, the focal point of the reflector is made to coincide with the focal point of the lens.

60 Then by lining the filament of the bulb with holes 40 and 50, the bulb, reflector and lens are in common focus.

65 A direct ray of light 32 from focal point 27 is bent by lens 20 into a ray 33, parallel with the axis of the reflector. Ray 26 ema-

nating from bulb 18 at focal point 27 is reflected by surface 29 to surface 30, thence along path 31 through focal point 27 coinciding with the direct ray 32 and is then bent by lens 20 along path 33 as was ray 32. 70

For convenience I term that portion of the light which is thrown directly from the bulb through the opening of the reflector, the direct cone of light, and that portion of light which falls on the interior of the reflector I 75 will refer to as the reflected light.

The portion of reflected light which originates in a cone symmetrical and opposite to the direct cone of light will be referred to as negative rays and the rest of the reflected 80 light, as positive rays.

It will be seen that all the positive reflected light will, by two reflections, be cast forwardly through the focal point coincident with the direct rays of light; and that all 85 the negative cone of reflected light, which is equal in volume to the direct cone of light will, by a series of four reflections, be cast forwardly through the focal point coincident with the direct rays of light. Therefore, the average number of reflections for the direct 90 light plus the negative is two, and as the positive light is reflected twice, the average number of reflections for all the light is two. 95

In the diagram Figure 6, the direct cone of light is included within the angle 35. The positive ray of light 36 strikes the reflector at the portion 37, is reflected therefrom to the portion 38 of the surface of the reflector and thence, 100 passes through the focal point 27, and out in the same path 39 as does a portion of the direct cone of light.

Considering now another positive ray 41: It will be noted that this ray strikes the portion 42 of the reflecting surface, is reflected therefrom to the surface portion 43 and passes through the focal point 27 and out through the opening 34 within the direct cone of light along the path 44.

A typical negative ray 45 of the reflected light will strike the portion 46 of the reflecting surface, will be reflected therefrom to the surface portion 47 and thence through the focal point 27, joining with the positive ray 36, to the portion 37 on the reflecting surface. From here it will be reflected to the portion 38 of the reflecting surface and thence through the focal point 27 and will pass out through the opening 34 within the direct cone of light along the path 39. 110

It will be seen that all reflected light will eventually be reflected about the interior of the reflector so as to pass through the focal point 27 of the reflector and hence out through the opening 34, merging with the unreflected rays so that with the exception of the light lost or absorbed all of the light from the focal point of the bulb will eventually pass out through the opening 34. If a lens is used as shown in Figure 1, then in as 115 120 125 130

much as the focal point of the reflector and the focal point of the lens are identical, all of the rays of light emanating at the focal point of the bulb will be thrown forwardly 5 from the lens in parallel rays. Any lens of proper focal length may be used to get desired effects other than parallel rays.

In the construction shown in Figure 11, the bulb 48 is itself formed in the eggshell 10 shape above described and is developed with a focal point 27 substantially around which is placed the filament 49. Therefore, when the bulb, except for the portion 34, corresponding to the opening in the front 15 end of the eggshell reflector, is surrounded by a reflecting shell 51 of the same shape, the result obtained is the same as that previously described with reference to Figure 6. The course of light may be shown by the 20 positive light ray 52 reflected by the portion 53 of the reflecting surface to the reflecting surface portion 54 from which it passes through the focal point 27 and continues outwardly through the opening 34 in the 25 direct cone of light.

Figure 8 shows another type of reflector embodying the same general principles and to be used as a headlight for automobiles, etc., although it appears to be different from 30 the type previously described, it is the same combination of a lateral and a rear mirror developed to one angle combined with parts of a lateral and rear mirror developed to another angle to make an unsymmetrical 35 finished unit. This type is designed to distribute all of the light rays below a horizontal plane passing through the focal point 27 and to have this light evenly distributed along the road in front of the headlight. 40 To accomplish this I make the reflector unsymmetrical with respect to its horizontal axis—in other words somewhat lopsided as shown by the shell 55.

The line 99 represents the road laid off in 45 equal lengths by lines perpendicular thereto. The radial lines from the focal point 27 meet these perpendiculars at the road line, in varying angles 87 to 92. The space between angle 92 and the horizontal axis 50 of the reflector may be divided into angles nearly equal to angle 92 or any other proportion desired. The lines bounding angles 87 to 98 are projected rearwardly through the focal point 27 and so limit the amount of 55 light which will be called negative reflected light and divide it into the same number of corresponding angles. The rest of the light from focal point 27 is divided into the same number of equal volumes. The equal 60 volumes of light are reflected through the various angles 87 to 98, and fall upon equal road distances or go further forward as predetermined by the angles 93 to 98. The theory of this reflecting surface is the same 65 as the other construction in that it is so

shaped that all reflected light, no matter where it strikes the interior of the shell, will eventually pass through the focal point 27 of the reflector, where the source of light 70 18 is positioned, and out through the opening co-incident with the direct rays. I prefer to have the opening 56 substantially semi-circular as shown in Figure 10.

Referring now to the diagrammatic view Figure 9 which illustrates the manner in 75 which rays will be reflected about the interior surface of the reflector of this special unsymmetrical design, the direct light from the focal point 27 passes out through the opening 56 in the usual manner, shaped as 80 a half cone, and a positive ray 57 will be reflected from the surface 58 to a surface 59, thence through the focal point 27 and out through the opening 56 along the path 60. Similarly a positive ray 61, will be reflected 85 from the surface at 62 to the surface at 63, thence through the focal point 27 and out through the opening 56 along the path 64. The negative light is reflected through two triangular paths into the direct light as it 90 was in Figure 6.

It will thus be seen that the invention contemplates a single reflector which may be considered as being composed of an infinite number of reflecting surfaces, the focal 95 points of all portions of the single reflector are identical. In other words, there is a single focal point and one only, so that in any construction of the invention, light rays radiating directly away from this focal 100 point pass directly out of the opening provided; or, if they fall on the interior of the reflector they will be so reflected about the interior surface of the reflector that they will eventually pass through this focal point 105 and thence out through the opening provided and will be projected forwardly coincident with the direct rays.

Having described my invention and illustrated it in various ways, I will now take 110 up the manner in which the contour of the reflector is developed and shall first explain the theory of equal volumes of light in adjacent cones of light in connection with the diagrammatic view of Figure 12, and shall 115 then discuss the theory of reflection and laying out by trial method the proper curve for the reflector in connection with the diagrammatic view of Figure 13.

Theory of equal volumes of light in adjacent cones of light.

The initial steps for producing the irregular curve shown by a longitudinal section taken through the axis of my reflecting shell 125 125 are shown in Figure 12 and may be described as follows:

With the center of the filament of a bulb as the center 1' of the drawing, a vertical line 2'—3' is drawn through 1' and is the 130

vertical center line of the drawings. A horizontal line 4'-5' drawn through the center 1' is the horizontal center line of the drawing and also the axis of rotation of the finished curve. The right side of the drawing represents the forward end of the reflector and the left side the rear end of the reflector. A line 6'-5'-8', drawn perpendicularly to the horizontal line 4'-5' at point 5' and of a length such that the distance 5'-6' equals the distance 5'-8', represents the cross-section of the desired field of light if intercepted at a point a distance from the center of the bulb equal to 1'-5'. As 6' and 8' are the top and bottom limits of the field, line 6'-1' and 8'-1', would if revolved on the axis 4'-5' limit a cone which represents the direct light to be thrown forward to field 6'-8' by the bulb at 1'.

Revolve lines 18'-1' and 16'-1' (which are extensions of straight lines 8'-1' and 6'-1') on axis 4'-5' and they will limit a cone of light at 18'-1'-16' which is equal to and symmetrical with the direct cone of light.

On the axis 4'-5' lay off any convenient number of equal distances each way from the point 1'. The more of these divisions used the more true a reflector curve will be developed. In this case four units are laid off each way at points 20', 21', 22', 23' and 25', 26', 27' and 28'. Vertical lines are erected through these points perpendicular to the axis 4'-5'. A circle with point 1' as its center is drawn thru the intersections of lines at 20' and 28' with the lines 8'-18' and 6' and 16' at points 30' and 40' and 38' and 48'. This intersects the other vertical lines at points 31' to 37' inclusive and 41' to 47' inclusive. Extended radial lines are drawn through these various points of intersection from point 1' which lines shall be known as lines 30' to 38' and 40' to 48'.

Revolving this plane drawing upon its horizontal axis 4'-5', would cause the various radial lines to bound cones each of which would have its apex at point 1'. The portions of the area of the sphere bounded by the planes developed by the parallel lines perpendicular to the axis are in the same ratio, one to another, as the distance between the parallel planes and in this case are equal. That part of the area of the sphere which lies within the cone whose apex is the center of the sphere is a correct measure of the spherical volume of light radiated from the sphere's center within the cone and may hereinafter be called the volume of the cone of light. The volume of cone of light 32'-1'-42' less cone 31'-1'-41' is equal to the volume of cone of light 31'-1'-41' less the volume of cone of light 30'-1'-40'. It is also equal to the volume of cone of light 33'-1'-43' less the volume of cone

32'-1'-42'; also equal to the volume of hemisphere of light 34'-1'-44' on the left hand less the volume of the cone of light 33'-1'-43'. In other words the various angles between two adjacent lines limit equal spherical volumes of light from the center of the sphere developed by rotation of the circle, except the cone of light which lies in the field of light and its opposite.

Line 39'-49' is drawn tangent to the circle already drawn and parallel to line 30'-40'. These lines are perpendicular to the horizontal axis 4'-5'. The space between lines 30'-40' and 39'-49' is divided by lines parallel thereto into eight equal divisions. These lines will intercept the circle at 61'-51', 62'-52', 63'-53', etc. Radial lines which shall be known as lines 61'-62'-63', 51'-52'-53', etc., drawn through these points from point 1' will, if revolved as set forth in the preceding paragraph limit cones of light in which the difference between volumes of two cones of light bounded by adjacent lines will equal the volume of the central cone of light 57'-1'-67'.

The last mentioned group of radial lines which pass through the center 1' and are extended to pass through the forward part of the circle cut it at points 70' to 78' and 80' to 88'; 70' lying in the same line as 50'; 71' as 51'; 72' as 52'; 80' as 60'; as 61' and 82' as 62', etc.

We now have the plane cross-section of the sphere divided into angles by lines radiating from its center, which lines, if revolved completely around the axis 4'-5', will cut each of the portions of the sphere's surface developed by arc 70'-78', arc 60'-68' into eight equal areas, and that portion developed by arc 30'-38' into eight equal areas. The areas developed by the arcs 70'-78' and 60'-68' will also be equal to each other.

In Figure 12 the following points are identical; viz., 30' and 60', 58' and 68', 40' and 50', 48' and 80', 78' and 88' and 38' and 70'. The circle intercepts line 8'-18' at point 30'-60' and point 48'-80', and line 6'-16' at point 40'-50' and 38'-70'; and line 4'-5' at point 58'-68' and point 78'-88'.

Discussion of theory of reflection and laying out by trial method the proper curve for the eggshell shaped reflector.

It is well known that in the reflection of light from a mirror the angle of reflection is equal to the angle of incidence and that a line perpendicular to the surface of a flat mirror will bisect the angle between the ray of light which falls upon the mirror and the ray of light reflected therefrom.

If then, light falls on a mirror and another flat mirror be set in the path of the

reflected light and so placed as to reflect this reflected light back to the source of light, the light follows a triangular path from the source to the first mirror thence to 5 the second mirror and thence to the source of light. These three lines of direction of the light will hereinafter be referred to as the triangular course of light and the first path be known as side A, the second as side B, and 10 the third as side C of the triangle. The source of light will be designated at 1^2 and is in the focal point 27 of the reflector; the first mirror will be designated as the lateral mirror or L, and the second mirror as the rear 15 mirror or R.

The bisector of the angle made by lines A and B is the perpendicular to the mirror L. The bisector of the angle made by lines B C is a perpendicular to the mirror R. 20 Therefore, to direct a ray of light from a given source falling upon a given point, to another point, bisect the angle made by the ray of light falling upon the first point and a line from that point to the second point. 25 Erect a plane perpendicular to the bisector at the point of the angle and place the mirror in the plane.

Lines in Figures 8 and 13 which bear the same relation to those as do those in Figure 30 12, bear the same numbers in the second power instead of the first power. In Figure 13 let line 1^2-30^2 be the side A of the first triangle. At any point on this line, such as point 30^2 , draw a line perpendicular to the 35 axis 4^2-5^2 to a point on the line 1^2-50^2 which will now be point 50^2 . In Figure 8 let line 1^2-30^2 be the side A of the first triangle. At any point on this line, such as point 30^2 , draw a line which shall meet the 40 axis at a point 50^2 . Point 50^2 shall be in this figure, on the axis 4^2-5^2 . The angle $30^2-50^2-1^2$ shall be less than a right angle. It will be noted that in Figure 8, line 50^2-1^2 and the axis 4^2-5^2 are identical; point 45 70^2 lies on the axis 4^2-5^2 ; and that points 40^2 and 50^2 are identical. The following description applies to Figures 8 and 13, except that in Figure 8 the second triangle has not been illustrated. This line is the second line 50 of the triangular course of light or line B. Line 1^2-50^2 is the third line or line C.

The bisector of the angle $1^2-30^2-50^2$ is the line 30^d-30^e . The perpendicular to 30^d-30^e is 30^L or a lateral mirror. The light 55 from this mirror follows the side of the triangular course of light B to point 50^2 . There a rear mirror is placed to direct the light back to the center 1^2 along line C. The bisector of the angle $30^2-50^2-1^2$ is the line 60 50^e-50^d .

The perpendicular to this bisector is the line 50^R-50^R which determines the location 65 of the rear mirror for the triangular course of light $1^2-30^2-50^2-1^2$. This triangular course of light carries light in both the fol-

lowing courses; $1^2-30^2-50^2-1^2$, and $1^2-50^2-30^2-1^2$. The former is the course we will take as the positive course, and the latter as the negative. The following development has been made for Figure 13 to illustrate the method of development. The same method can be followed to develop the curves for Figure 8, except that the various radial lines within the lines A and C would conform to the rearward extension through point 27 of the rays 87 to 98. On line 1^2-31^2 a trial point 31^3 is selected for the location of the lateral mirror. This point will be nearer to the center 1^2 than is the intersection of lateral mirror 30^L with the line 31^2 , and nearer to the center 1^2 than is the point 31^2 . Point 31^3 is then used as a point for a second lateral mirror which shall reflect the light from center 1^2 along line 31^3 to a point 51^3 on line 51^2-1^2 . Line 31^d-31^e is a bisector of the angle $1^2-31^3-51^3$. Line 31^L is perpendicular to this bisector and is the second lateral mirror.

Point 51^3 is nearer the center 1^2 than is the intersection of the rear mirror 50^R with the line 51^2-1^2 and farther than is the point 51^2 .

Line 51^d-51^e is the bisector of the angle $31^3-51^3-1^2$.

Line 51^R is perpendicular to this bisector and is used as the rear mirror for this triangular course of light.

If the trial points used cause the mirrors 31^L and 30^L to intersect each other at a point nearly equidistant from points 30^2 and 31^3 and the rear mirrors 50^R and 51^R to intersect each other nearly equidistant from points 50^2 and 51^3 , or so that each lateral mirror, when rotated around axis 4^2-5^2 , would intercept equal volumes of positive 105 light, and each rear mirror would intercept equal volumes of negative light, then the trial points 31^3 and 51^3 may be fixed as correct. If not, they must be changed to bring about the above results.

Then in the same manner select a point on lines 32^2-1^2 and a point on line 52^2-1^2 and repeat the same method for developing another pair of lateral and rear mirrors.

These mirrors must bear the same relation to 31^L and 51^R that 31^L and 51^R bear to 30^2 and 50^R .

Repeat the operation for each of the following pairs of lines radiating from the center 1^2 ; 33^2 and 53^2 , 34^2 and 54^2 , 35^2 and 55^2 , 36^2 and 56^2 , 37^2 and 57^2 , 38^2 and 58^2 .

This develops a lateral reflector composed of short flat mirrors which reflect positive light to a rear reflector likewise composed of short flat mirrors which re-reflects the light to the original source of light at the focal point and forwardly through the same, coincident with the direct rays of light which fall upon the desired field of light. Negative light will also be reflected through 130

two triangular paths as hereinbefore described.

By increasing the number of radial lines the flat mirrors become smaller and increase in number proportionately. By drawing on a very large scale and using small divisions the mirrors can be brought to very small size. Then by using the mirror surfaces as tangents draw a pair of curves through the 10 intersections with the radial lines. These curves will not be regular curves but slow spirals.

By rotating the curves thus formed around the axis 4°—5° the curves will meet 15 at points 30°—50° and close together the rear and sides, leaving open only that portion which lies within the forward cone of light 70°—1°—80°. Thus the contour of the egg-shell reflector is developed.

20 In Figure 7 there are shown six triangular paths of light and their lateral and rear mirrors upon which, two curves may be drawn, using the mirrors as tangents. Revolving these curves around the axis would 25 develop the contour of the novel egg-shell reflector.

This method of developing curves applies when the top, bottom and sides are all to be 30 symmetrical; namely, when the field of light is to be round and have equal distribution 35 of light over equal areas equidistant from the center of the field. It should be noted that openings limiting direct cones of light of different angles have been shown in the drawings and that the egg-shell reflector can be developed for different sized fields of light.

If more light is to be placed in one half 40 of the field than in the other, the top lateral and bottom rear mirrors must be developed together and the bottom lateral and top rear mirrors together, in the same general way as above described, but by using radial lines in such relation as to give the 45 desired proportion of light over the field. In Figure 8 the top half of the field, i. e. above the axis, receives no reflected light, and all of the reflected light is concentrated in the lower half of the field; and it will 50 also be noted that the line 30°—40° will not be perpendicular to the axis but at an angle which may be found by trial, that will cause both upper and lower rear mirrors to coincide.

55 If the test reflector when completed does not give the exact proportion of light desired, a photometric test should be made and a new reflector designed with the radial lines which bound the rays 87 to 98 slightly 60 changed in proportionate relation so that the more light may be placed in too dim areas and vice versa to bring the light to the distribution originally desired.

Thus if the ray 90 is too weak, the radial 65 lines from 1° which bound ray 90 should be

brought closer together so as to concentrate the same amount of light into a smaller area upon the road. If it were too bright, the boundary lines would be spread apart slightly. Similar changes would be made 70 for any other rays which were not in the proper ratio of brightness. Then the balance of the rays would be enlarged or decreased in uniform ratio to account for the surplus or diminished space. 75

While I have described my invention and illustrated it in several designs, I do not wish it understood that I limit myself to this construction, as it is evident that the application of the invention may be varied 80 in many ways within the scope of the following claims:

1. A reflector substantially of egg-shell shape having a single focal point and adapted to have a source of light positioned substantially at said focal point, the reflector having an opening at one end adjacent said focal point, said opening to be of a dimension sufficiently large to permit free passage of all light rays emanating from said source 90 of light and tending to fall upon the desired field of light, and said dimension being sufficiently limited to cause the reflector to intercept all light rays so emanating except those tending to fall upon said field. 95

2. A reflector having a single focal point and having an opening at one end adjacent to said focal point, the interior surface of said reflector being so curved that all light falling upon the interior of said reflector from said focal point will be reflected through said focal point by a plurality of reflections and out through said opening coincident with the direct rays passing through said opening. 100

3. In a reflector means having a single focal point and comprised of a plurality of rear mirrors merged one into the other and a plurality of lateral mirrors merged one into the other, said mirrors being so positioned that all lights thrown upon a lateral mirror from or through a source of light positioned at the focal point of the reflector, will be reflected to a rear mirror and thence through the source of light to the desired field of light, and all the light thrown upon a rear mirror will be reflected to a lateral mirror and thence to and through the source of light to an opposite lateral mirror and thence to a rear mirror and back through the source of light to the desired field of light. 110 115

4. In a reflector of general egg-shell shape, the combination with the inner reflecting surface thereof, of a source of light positioned at the focal point of said reflector, the contour of the inner surface of the reflector being such that all light radiated from the focal point and received by the inner surface of the reflector will be reflected through the 120 125 130

focal point by a plurality of reflections, the last reflection throwing all the reflected light through the focal point and thence out the opening, coincident with the unreflected 5 light, to the desired field of light.

5. In a reflector means, the combination of a reflector of general egg-shell shape having a single focal point adjacent an opening at its smaller end toward the desired field of 10 light, a source of light positioned at the focal point of said reflector, the contour of the inner surface of said reflector being such that a portion of the light from said source will pass directly to said field of light and 15 that all the other light will be reflected within said reflector, except that lost in absorption, and will be reflected back through said focal point and out to said field of light.

6. In a reflector apparatus, the combina-

tion of a reflecting means adapted closely to 20 fit an electric lamp bulb of substantially egg-shell shape, said reflecting means providing a reflector having a single focal point within the bulb adjacent the small end thereof, said reflector having an opening at the small end 25 thereof to permit passage of light.

7. A light reflector adapted to be positioned about a source of light and shaped to provide an irregularly curved internal reflecting surface having a single focal point, 30 a source of light at said focal point, the reflector having an aperture adjacent to said focal point whereby all internally reflected rays pass through the source and outwardly through the aperture. 35

In witness whereof, I have hereunto set my hand this 17th day of July 1922.

TAYLOR CALHOUN RHODES.
